UNITED STATES PATENT OFFICE.

WARREN H. WILDRICK, OF PHILLIPSBURG, NEW JERSEY.

SACK-CLEANER.

1,115,357.

Specification of Letters Patent. Patented Oct. 27, 1914.

Application filed February 24, 1914. Serial No. 820,773.

To all whom it may concern:

Be it known that I, WARREN H. WILDRICK, a citizen of the United States, residing at Phillipsburg, in the county of Warren and 5 State of New Jersey, have invented certain new and useful Improvements in Sack-Cleaners; and I do declare the following to be a full, clear, and exact description of the invention, such as will enable others skilled 10 in the art to which it appertains to make and use the same.

This invention relates to improvements in brushing and scrubbing and more particularly to bag cleaners.

15 The object of the invention is to provide a simple and efficient cleaning apparatus for bags made of fabric or textile material after the same have been used in order to clean them for refilling and subsequent use. For 20 example, in the use of bags for cement a great deal of the material works into the fabric of the bag and remains there after the bag has been emptied and laid aside. This is also true of flour and it is desirable to remove 25 this material from the empty bag in order to have a practically clean bag for refilling and at the same time not to mutilate the bag during the cleaning operation.

With the above and other objects in view, 30 the invention consists of certain novel features of construction, and the combination and arrangement of parts as will be more fully described and claimed.

In the accompanying drawings:—Figure 35 1 represents a side elevation partly in section of this improved bag cleaning apparatus; Fig. 2 represents a similar view taken in a plane at right angles to Fig. 1; Fig. 3 is a top plan view thereof; Fig. 4 is a trans- 40 verse section taken on the line 4—4 of Fig. 2.

In the embodiment illustrated, a supporting frame 1 is shown in which a horizontally disposed driving shaft 2 is mounted, power for which may be supplied from any suitable source, a driving pulley 3 being here shown adapted for connection with the source of power. A fan 4 is mounted on this shaft 2 and is adapted to be driven thereby and is surrounded by a suitable casing 5 from which an air pipe 6 to be described leads. An upright shaft 7 is also mounted in the frame 1 in a plane at right angles to the shaft 2 and is provided on its lower end with a beveled gear 8 which 55 meshes with a similar gear 9 on the shaft 2

whereby rotary motion is imparted to the shaft 7 from the shaft 2 for a purpose to be described. The shaft 7 constitutes the axle of a revoluble spiral brush 10 the bristles 10' of which are so arranged as to conduct the sacks fed into the top of the apparatus downward. This rotary brush is inclosed by a foraminous cylinder 11 preferably constructed of woven wire but it may be of any other suitable or desired material. This cylinder is shown composed of a screen disk-like bottom 12 and an annular head 13 which are connected at intervals by bars 14 and around these bars 14 is arranged the foraminous covering of the cylinder. A brace ring 15 encircles the bars intermediately of their ends preferably midway thereof to prevent bulging of the cylinder. The bars 14 are designed in addition to forming longitudinal bracing elements or supports for the cylinder 11 to constitute scrubbing elements between which and the bristles 10' of the brush 10 the bags are designed to pass whereby they are thoroughly cleansed of the material impregnating them.

The air discharge pipe 6 which leads from the casing 5 of the fan 4 is here shown extended horizontally below the cylinder 11 and provided with a plurality of upwardly extending discharge nozzles 16. Said pipe 6 is then extended upwardly into upright position substantially the full length of said cylinder and is provided with a plurality of longitudinally spaced laterally extending discharge nozzles 16' arranged on its inner 90 face opposite the cylinder 11. These nozzles 16 and 16' are designed to discharge air under pressure into the cylinder through the foraminous covering and bottom thereof to assist the bristles and scrubbing boards in 95 their cleansing action. This cylinder 11 is provided at its lower end with a discharge spout or outlet 17 through which the cleansed bags are adapted to be discharged onto a suitable conveyer 18 which carries 100 them to a suitable place of deposit. Disposed adjacent the cylinder 11 is an endless conveyer 19 mounted on suitable pulleys 20 and 21 suitably supported above and below the ends of the cylinder 11. The pulley 20 is here shown mounted on the driving shaft 2 from which it receives its motion for driving the conveyer. This conveyer is provided with a plurality of longitudinally spaced flights 22 which are adapted to en- 110

gage the bags to be cleaned and carry them forward to the top of the apparatus and discharge them into the chute 23 which opens into said cylinder 11 and through which the 5 bags are fed to said cylinder.

The pulley 20 is disposed in a hopper 24 in which the bags to be cleaned are disposed and the turning of the pulley and consequent turning of the belt 19 lifts by means 10 of the flights 22, the bags upwardly and after they are discharged through the spout or chute 23 they are carried downwardly by the spiral brush 10 and thoroughly cleansed by the brushing and scrubbing action exerted thereon by the bristles 10' of said brush and the bars 14.

The bristles 10' of the brush 10 are here shown of equal length and are constructed of any suitable material for exerting the 20 most effective action on the bags to be cleaned it being understood that these bags are first preferably turned before being fed to the cylinder.

The conveyer 18 which conducts the discharged cleaned bags to a point of deposit may be driven by any suitable means but is here shown driven by pulleys which receive their power from the driving shaft 2.

I claim as my invention:—

30. 1. A sack cleaner comprising an upright foraminous cylinder, a brush revolvably mounted in said cylinder, means arranged opposite said cylinder for discharging air under pressure thereinto, and means for rotating said brush.
2. A sack cleaner comprising a foraminous cylinder, a revolvably mounted spiral brush disposed in said cylinder, means for revolving said brush, means for discharging 40 the article to be cleaned into the top of said cylinder, and an air discharge pipe extending longitudinally outside said cylinder and provided with a plurality of discharge nozzles opening onto the cylinder.
45. 3. A sack cleaner comprising a foraminous cylinder, a spiral brush mounted in said cylinder, scrubbing elements positioned in said cylinder for coaction with said spiral brush, means for feeding the articles to be 50 cleaned into the top of said cylinder, a pipe arranged longitudinally of said cylinder on the outside thereof and provided with a plurality of nozzles discharging onto said cylinder.

inder and means for supplying compressed air to said pipe.

4. A sack cleaner comprising a supporting structure, a horizontally disposed driving shaft mounted therein, an upright shaft disposed at right angles to said driving shaft, coöoperating elements on said shafts whereby said upright shaft is driven by said driving shaft, a brush mounted on said upright shaft, a cylinder encircling said brush and comprising a reticulated bottom and an open top, a plurality of bars connecting said top and bottom, a foraminous cover secured to the outer faces of said bars, a bracing element encircling said bars intermediate of the length thereof, and means for discharging air under pressure onto said 70 cylinder.

5. A sack cleaner comprising a supporting structure, an upright spiral brush mounted therein, means for revolving said brush, a foraminous cylinder encircling said brush 75 and including a reticulated bottom and an annular top, spaced bars connecting said top and bottom and having their inner faces constructed to form a scrubbing board, a foraminous covering encircling said bars, 80 and a discharge spout at the lower end of said cylinder.

6. A sack cleaner comprising a supporting structure, a horizontally disposed driving shaft mounted therein, a fan fixed on said shaft and revolvable therewith, a casing enclosing said fan, an upright shaft arranged at right angles to said driving shaft, said shafts being provided with beveled gears meshing with each other, a spiral brush 90 mounted on said upright shaft, a foraminous cylinder encircling said brush, a pipe connected with said fan casing and disposed longitudinally of said cylinder on the outside thereof and provided with a plurality 95 of longitudinally spaced discharge nozzles positioned to discharge air onto said cylinder.

In testimony whereof I have hereunto set my hand in presence of two subscribing witnesses.

WARREN H. WILDRICK.
